CLAIM

The ornamental design for a blood flow restriction exercise strap, as shown and described.

DESCRIPTION

FIG. 1 is a top front perspective view of the blood flow restriction exercise strap showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right elevation view thereof; and,

FIG. 7 is a left elevation view thereof.

The broken lines shown in the drawings illustrate portions of the blood flow restriction exercise strap that form no part of the claimed design.
